UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

SLACK-ADJUSTER MECHANISM.

Application filed July 3, 1922. Serial No. 572,397.

To all whom it may concern:

Be it known that I, LOREN L. WHITNEY, a citizen of the United States, residing at Hammond, in the county of Lake and State 5 of Indiana, have invented certain new and useful Improvements in Slack-Adjuster Mechanism, of which the following is a specification.

This invention relates to slack adjuster 10 mechanism which is adapted for use particularly in connection with brakes.

The object of this invention is to provide slack adjuster means having relatively few parts, all of which are simple, are easily and 15 simply assembled and which cooperate in a manner to meet all of the requirements for the intended use.

This and other objects are accomplished by means of the arrangement disclosed on 20 the accompanying sheet of drawings, in which—

Figure 1 is a side elevation of a slack adjuster block;

Figure 2 is an end view thereof;

Figure 3 is a side elevation of the same slack adjuster block mounted within an adjuster jaw;

Figure 4 is a plan view of the same arrangement as shown in Figure 3;

Figure 5 is a transverse sectional view 30 through the adjuster jaw and block showing flanges on the block bent into a position to permit the passage of the block into the jaw; and

Figure 6 is a similar sectional view taken in the plane of line 6—6 of Figure 3 showing the normal relative positions of the adjuster jaw and block after the flanges are bent into their normal operative positions.

The various novel features of the invention will be apparent from the following description and drawings, and will be particularly pointed out in the appended claims.

Referring to the figures of the drawings, it will be noted that my invention relates to a slack adjuster including a relatively movable member 10 having a jaw portion 11 in the form of a closed loop having sides 12.

An adjuster block 13 is mounted within the 50 jaw portions 11 of the member 10 and has two sets of flanges 17 and 18 which normally embrace the edges of the sides 12 for retaining the adjuster block within the jaw and

for guiding the relative movements between 55 the jaw member 11 and the block 13.

Referring particularly to Figures 1, 2 and 4, it will be noted that the block 13 is in a single piece and has spaced arms 14 between which it will be understood a brake 60 lever, not shown, is received. The brake lever fulcrum pin, also not shown, is received in the bifurcations 15 at the ends of the arms and retained in such position by keys, not shown, extending through the openings 65 16 in the ends. The brake lever, its fulcrum pin and the keys are not shown for purposes of clearance, and also for the reason that such elements form no part of the invention. The outwardly projecting flanges 17 at the 70 upper part of each arm 14 remain in their normal right angle position with respect to the arms 14 for cooperating to guidedly maintain the block 13 in operative position within the jaw 11 after the block is once 75 mounted therein. The other flanges 18 also cooperate with the flanges 17 in this respect. The flanges 18, however, are bent into the planes of the arms 14 preparatory to placing the block 13 within the jaw 11. The 80 flanges 18 are shown bent downwardly in Figures 1, 2 and 5. To facilitate the bending of the flanges 18, the lower part of each of the arms 14 is recessed at 19.

In assembling the block 13 with respect 85 to the jaw 11, the flanges 18 are either in, or bent into the same plane with the arms 14, whereupon the block 13 is passed between the sides 12 of the jaw 11 until the flanges 17 pass into engagement with said 90 side members 12, as shown particularly in Figure 5, whereupon the flanges 18 may be bent upwardly into a right angle relationship with respect to the arms 14, as shown in Figure 6, in which position the flanges 95 18 and 18 are in their normal positions for maintaining the operative relationship between the adjuster block 13 and adjuster jaw 11.

Any suitable means, such as an adjusting screw 20, may be employed for giving a relative movement to the block 13 and jaw 11 for varying or adjusting the slack in accordance with requirements. It will be understood that if the adjusting screw 100 20 is rotated in one direction there will be a relative movement between the block 13 and jaw 11 in one direction, and if rotated 105

in the opposite direction there will be a relative movement between the block and jaw in the opposite direction.

It is my intention to cover all modifications of the invention falling within the spirit and scope of the following claims.

I claim:

- 10 1. A slack adjuster including, in combination, an adjuster jaw, and an adjuster block having flanges cooperating with said jaw whereby the block is adjustably and guidedly mounted in said jaw, certain of said flanges being capable of being placed in different relative positions, in one of said positions permitting said block to be applied to said jaw and in another position after being applied to said jaw retaining the block therein.
- 15 2. A slack adjuster including, in combination, an adjuster jaw, and an adjuster block having arms with flanges which cooperate with said jaw for maintaining said

block in position with respect to said jaw, the flanges on one of said arms being capable of being placed in different relative positions, in one of said positions permitting the passage of said flanges during the application of said block to said jaw and in another position cooperating with said jaw for retaining the block in operative association with said jaw.

3. A slack adjuster including, in combination, an adjuster jaw, and an adjuster block adjustably mounted within said jaw, said block having spaced arms with laterally extending flanges, certain of said flanges being capable of being bent into the plane of said arms to permit the block to be applied to said jaw and then bent back at right angles to said arms to retain said block within said jaw.

Signed at Hammond, Indiana, this 22nd day of June, 1922.

LOREN L. WHITNEY
